UNITED STATES PATENT OFFICE.

GERRIT VON DAAM, OF SCRANTON, PENNSYLVANIA.

AIR-HEATING DEVICE FOR STOVES.

1,027,944.

Specification of Letters Patent.

Patented May 28, 1912.

Application filed April 1, 1911. Serial No. 618,311.

To all whom it may concern:

Be it known that I, GERRIT VON DAAM, a citizen of the United States, residing at Scranton, in the county of Lackawanna and 5 State of Pennsylvania, have invented new and useful Improvements in Air-Heating Devices for Stoves, of which the following is a specification.

This invention relates to air heating devices for stoves or furnaces, the object of 10 the invention being to provide a device of this character which can be applied or attached to any well known form of stove or furnace without changing the construction 15 of the same, the device being designed to supply air from the outside to the fire-pot and being positioned so that the air while being conveyed to the fire-pot will be heated so that the air when discharged into the 20 fire-pot may be thoroughly mixed with the unconsumed gases and thereby promote proper combustion.

In the drawings, forming a portion of 25 this specification and in which like numerals of reference indicate similar parts in the several views:—Figure 1 is a plan view of a range showing my improved air heating device applied thereto. Fig. 2 is a plan view of the device removed from the range. 30 Fig. 3 is a section on line 3—3 of Fig. 1. Fig. 4 is a section on line 4—4 of Fig. 2. Fig. 5 is a plan view of a slightly modified form of my invention. Fig. 6 is a modified form of the device illustrated in Fig. 1 35 showing my invention applied to a stove having a single fire-pot.

In the preferred embodiment of my invention I provide an air heating and feeding device which includes a tube 1 of coil 40 form which is provided intermediate of its ends with a plurality of loops 2. In this form of my invention the device is used in connection with a stove A having a pair of fire-pots B. The tube 1 has one of its terminals attached to a conveying tube 3 disposed below the plane of the tube 1 and having oppositely extending portions which extend in the direction of the opposite fire-pots B, each of such portions having a 45 nozzle or jet head 4 which latter is bent inwardly intermediate its ends and in advance of the conveying tube 3, as at 4', to provide a deflector, the deflector serving to distribute the air evenly throughout the jet heads 50 4, which are perforated, at 5. The perforated side of each head is positioned with

respect to the corresponding fire-pot so that the air can be discharged directly thereinto and across the path of the rising gases. The opposite terminal of the tube is provided with a vertical branch portion 6 which is preferably exteriorly threaded, at 7, to receive a short sleeve 8. This sleeve extends through an opening 9 in the stove lid 10, the outer end of the sleeve having 65 openings 11 therein which may be covered or uncovered by the damper 12, shown in Fig. 3 of the drawings.

The tube 1 has portions extended into grooves or concavities 13 on the inner surface of the supporting legs 14. These legs depend from the tube and are designed to rest on the wall 15 of the stove, the said wall in this instance forming a part of the discharge conduit C for the smoke and gases, the said conduit being in communication with the pipe 16 as usual. With a view of retarding the discharge of the gaseous products from the stove and for allowing a perfect mixture of the air with the unconsumed gases the pipe 16 is provided with a controlling damper 17. The legs 14 are provided with registering or alining grooves 18 in which a clamping band 19 is fitted and secured, at 20, to the legs. This 70 construction is such that when the clamping band is engaged with the legs as described, the legs will be securely confined in embracing engagement with the tube 1. The tube 1 is horizontally disposed and at the will 75 of the operator the damper 11 may be controlled manually so as to permit any required admission of air from the outside to the tube. The disposition of the tube in the channel or conduit C is such that the 80 tube will be fully exposed to the heat and in consequence thereof the air as it is spread through the tube will be heated thoroughly 85 before it is discharged into the fire-pot.

In the form of my invention shown in 90 Fig. 5, the tube 1^a is in the form of a serpentine coil, one branch or terminal thereof being extended outwardly, at 21, below the plane of the tube 1^a and provided with a head 22 which is formed with oppositely extending discharge portions 23, perforated, at 24. The opposite terminal 25 of this tube is adapted to be extended through the stove lid as described in the preferred form 95 of my invention.

In the construction shown in Fig. 6, I have illustrated the device applied to a

stove having a single fire pot and for this purpose the device is provided with only one nozzle or jet head. In other respects this form of my invention is identical to 5 that shown in Fig. 1 already described, and therefore a further description of this figure is not deemed necessary.

10 The discharge end of the air heating and feeding tube shown in Fig. 1 of the drawings is located above the plane of the fire-pot and adjacent to one side thereof and adjacent to the back of the fire-pot so as to retard the movement of the rising gases at the effective discharge end of the fire-pot.

15 In the construction shown in Fig. 6, I have shown the device applied to a stove having a single fire-pot and for this purpose it is provided with only one nozzle or jet head. In other respects this form of 20 my invention is identical to that shown in Fig. 1 and already described, and therefore, a further description of this figure is not deemed necessary.

I claim:

25 1. In an air heating and feeding device for stoves, a fire pot, a tube located above the plane of the fire pot and adjacent thereto and having an intake end and a discharge end located above the plane of the fire pot 30 and adjacent one side thereof, supporting feet for the tube, and a band extending around the feet and operating to hold the feet in embracing engagement with the tube.

35 2. An air heating and feeding device of the character described comprising a fire pot, a tube located above the plane of the fire pot and adjacent thereto and having an air intake portion and an air discharge portion located above the plane of the fire pot 40 and adjacent one side thereof, grooved feet having their grooved portions fitted to the tube, and a band extending around the feet and connecting them with each other and operating to hold the feet operatively associated with the tube.

45 3. In an air heating and feeding device for stoves, a stove including a fire pot therefor, a coiled tube located above the plane of the fire pot at one side thereof and in the 50 path of the products of combustion and provided at one end with an air intake portion, the opposite end of said tube terminating in a straight conveying tube located in a plane below the plane of the coil, the said conveying tube terminating in jet heads projecting laterally therefrom and located above the 55 plane of the fire pot and adjacent one side thereof so that the air may be directed into the fire pot and across the path of the rising gaseous products.

4. In an air heating and feeding device for stoves, a stove including a fire pot therefor, a coiled tube located above the plane of the fire pot at one side thereof and in the path of the products of combustion and provided at one end with an air intake portion, the opposite end of said coiled tube terminating in a straight conveying tube, a jet head connected to said conveying tube and projecting laterally therefrom, said jet head being formed intermediate its ends to provide a deflector, said deflector being arranged in advance of the conveying tube so that the air may be evenly distributed throughout the jet head, and means for supporting the tube. 65 70 75

5. In an air heating and feeding device for stoves, a stove including a fire pot therefor, a coiled tube located above the plane of the fire pot and at one side thereof, said tube being formed to provide a plurality of loops intermediate its ends and provided at one end with an air intake portion, a conveying tube connected intermediate its ends to said coiled tube, jet heads arranged upon each end of said conveying tube and projecting laterally therefrom, and means for supporting the coiled tube. 80 85

6. In an air heating and feeding device for stoves, a stove including a fire pot therefor, a coiled tube located above the plane of the fire pot and at one side thereof and in the path of the products of combustion and provided at one end with an air intake portion, a conveying tube connected to the opposite end of said coiled tube and located in a plane below the plane of the coil, a jet head connected to said conveying tube and projecting laterally therefrom, and means for supporting the coiled tube. 90 95 100

7. In an air heating and feeding device for stoves, a stove including a fire pot therefor, a coiled tube provided at one end with an air intake portion, a conveying tube connected to the opposite end of said coiled tube and located in a plane below the plane of the coil, a jet head connected to said conveying tube and projecting laterally therefrom and located above the plane of the fire pot and adjacent one side thereof so that the air may be directed into the fire pot and across the path of the rising gaseous products, and means for supporting the coiled tube. 105 110

115 In testimony whereof I affix my signature in presence of two witnesses.
